Primary Examiner — Joseph Kukella*Assistant Examiner* — Darryl J Dardenne(74) *Attorney, Agent, or Firm* — Hall Estill Law Firm(57) **CLAIM**

The ornamental design for a tea infuser, as shown and described.

DESCRIPTION

FIG. 1 is a top, perspective view showing a first embodiment of a new design for a tea infuser.

FIG. 2 is a front view of the tea infuser of FIG. 1.

FIG. 3 is a rear view of the tea infuser of FIG. 1.

FIG. 4 is a right side view of the tea infuser of FIG. 1, of which the left side is a mirror image.

FIG. 5 is a top view of the tea infuser of FIG. 1; and, FIG. 6 is a bottom view of the tea infuser of FIG. 1.

In the drawings, the broken lines depict environmental subject matter only and form no part of the claimed design.

1 Claim, 6 Drawing Sheets(56)
